ELECTRICAL DELAY NETWORK

Application filed September 11, 1926. Serial No. 134,929.

This invention relates to an electro-mechanical device and more particularly to a combined electrical and mechanical device in which the mechanical part is designed to simulate certain electrical circuits or parts of circuits.

In various electrical circuits, such as transmission lines, it has been found advantageous to introduce electrical apparatus, such as correcting networks to modify the characteristics of the line as a whole or artificial line networks to balance or to terminate a line. The precision with which a desired result, such as a simulation by a correcting network or an artificial line, may be obtained will in general depend on the number of degrees of freedom in the apparatus, and in the illustrations given, this refers to the number of elements of capacity, inductance or resistance present. In correcting networks and artificial lines it has been convenient to build them of a series of sections of such elements, the greater the number of sections used the greater the degree of simulation possible. In some cases, the cost places a sharp prohibition to the use of these networks or limits the number of sections which is feasible. Various attempts have been made, with some success, to devise simplified and composite circuits which will be more economical but this has only partially solved the problem. In this invention, we provide for substituting mechanical devices, in whole or in part, for electrical circuits or parts thereof.

An object of the invention, then, is to devise a mechanical means, properly associated with the electric lines or circuits, which shall serve as the equivalent of electrical networks. A further object is to develop design formulae by which a mechanical device may be constructed to simulate a particular electrical network or to exhibit electrical characteristics on a quantitative basis.

The invention will be better understood by reference to the following specification and accompanying drawing in which Figure 1 represents a simple form of electro-mechanical device whereby electrical reactance may be obtained by mechanical means; Fig. 2 shows another and preferred means for this

purpose; Figs. 3 to 6 show parts of electric circuits to be simulated; Figs. 7 and 8 are diagrams used in explaining the operation of the invention; Fig. 9 is a curve showing various relations necessary for our method of design and Fig. 10 shows a circuit which is the equivalent of the device of Fig. 2.

In the following analysis of the combined electrical and mechanical device it has been found convenient to make use of certain analogies which exist between electrical systems and mechanical systems thus simplifying the necessary equations. These analogies are not merely qualitative but quantitative and identical, and the same symbols will be used. The corresponding quantities in the two systems, which we will encounter, are:

Electrical system	Mechanical system	
Charge	Displacement	
Current	Velocity of mass	70
Electromotive force	Force	
Inductance	Mass	
Capacity	Reciprocal of stiffness or elasticity	65
Resistance	Friction	75

Referring more particularly to Fig. 1, we shall now prove that for the simple mechanical device as shown in that figure, the electrical impedance is given by

$$Z_e = j\omega L_0 + \frac{1}{j\omega C_1} + \frac{y^2 L_0^2 i_0^2 a^2}{Z_m}$$

where a L_0 is the change in L_0 per unit of displacement q_2 , y is the ratio of mutual inductance of L_0 and L_0' to L_0 , and Z_m is the mechanical impedance of the system.

This drawing shows a magnet M with two windings on its pole and the mass L_2 so placed that the pull of the magnet is opposed by the spring C_2 . One winding of the magnet is connected to a source of direct current in series with a large inductance W which serves to keep the current i_0 constant. The other winding is connected to a source of alternating voltage E with the condenser C_1 in series.

We can derive the electrical impedance of this system by the use of Lagrange's equation of motion which is shown below slightly

modified to include an outside force not accounted for in T and V.

$$\frac{d}{dt} \frac{(\delta T)}{(\delta i)} - \frac{\delta T}{\delta q} + \frac{\delta V}{\delta q} = E \quad (1)$$

Here T is the kinetic energy, V is the potential energy, q is the coordinate with respect to which these energies are taken and i is $\frac{dq}{dt}$.

10 E is the outside force (E. M. F.) acting upon the system.

In this system the kinetic energy may be expressed as follows:

$$15 T = \frac{1}{2} L_0' (1 + a_1 q_2) i_0^2 + \frac{1}{2} L_0 (1 + a_2 q_2) i_1^2 + M i_0 i_1 (1 + a q_2) + \frac{1}{2} L_2 i_2^2 \quad (2)$$

Where L_0' is the inductance of the D. C. coil, L_0 is the inductance of the A. C. coil, M is the mutual inductance of the two and a a_1 a_2 , a_2 q_2 are the factors of change of inductance

$$25 \frac{d}{dt} \left[(1 + a_2 q_2) L_0 i_1 + (1 + a q_2) y L_0 i_0 \right] + \frac{q_1}{C_1} = E = L_0 \frac{di_1}{dt} + a_2 i_2 i_1 L_0 + a_2 q_2 L_0 \frac{di_1}{dt} + a i_0 i_2 y L_0 + \frac{q_1}{C_1} \quad 90$$

due to displacement, the a 's being constants. L_2 is the mass of the movable rod and i_2 is the velocity of the mechanical system. i_0 and i_1 are the D. C. and A. C. currents, respectively.

35 ly, as shown on the figure. If now,

$$L_0' = x L_0 \text{ and } M = y L_0$$

Equation (2) becomes

$$40 T = L_0 \left[\frac{x}{2} i_0^2 (1 + a_1 q_2) + \frac{1}{2} i_1^2 (1 + a_2 q_2) + y i_0 i_1 (1 + a q_2) \right] + \frac{1}{2} L_2 i_2^2 \quad (3)$$

In order to get the potential energy of the whole system, we must know the force acting upon the mass L_2 , which is caused by the spring:

50

$$F_m = \frac{D}{C_2} + \frac{q_2}{C_2}$$

55

$$\left[\frac{d}{dt} L_2 i_2 \right] - L_0 \left[a_1 \frac{x}{2} i_0^2 + \frac{1}{2} a_2 i_1^2 + a y i_0 i_1 \right] + \frac{D}{C_2} + \frac{q_2}{C_2} = 0$$

Here D is the distance the spring has been stretched by the force of the constant current i_0 and q_2 is again displacement. It should be noted that C_2 is the reciprocal of the elastance of the spring. It is used for convenience so that the equations will look more like electrical equations.

The potential energy of the whole system will be the sum of the potential energy in the

electrical system and the potential energy in the mechanical system. Thus:

$$V = \frac{1}{2} \frac{q_1^2}{C_1} + \int_{-D}^{\frac{q_2}{C_2}} \left(\frac{D}{C_2} + \frac{q_2}{C_2} \right) dq_2 \quad 70$$

where q_1 is the charge of the condenser C_1 . Solving, we get:

$$V = \frac{1}{2} \frac{q_1^2}{C_1} + \frac{D q_2}{C_2} + \frac{1}{2} \frac{q_2^2}{C_2} + \frac{D^2}{2 C_2} \quad 75$$

We may now substitute in the Lagrange

Equation (1). Treating q_1 and i_1 as the variables and differentiating V and T in (4) and (3) with regard to these, we obtain the La- 85 grange equation for the electrical system:

Since we are dealing with sine waves, we are justified in substituting jp for $\frac{d}{dt}$ and $\frac{i}{jp}$ for q , where $j = \sqrt{-1}$, thus: 95

$$jp L_0 i_1 + a_2 q_2 jp L_0 i_1 + a_2 L_0 i_1 i_2 + a y L_0 i_0 i_2 + \frac{i_1}{jp C_1} = E$$

$a_2 q_2 jp L_0 i_1$ and $a_2 i_1 i_2 L_0$ are negligible second order terms, therefore: 100

$$E = i_1 \left(jp L_0 + \frac{1}{jp C_1} \right) + a y i_0 i_2 L_0 \quad (5)$$

Now treating q_2 and i_2 as the variables and differentiating Equations (3) and (4) with regard to them and substituting in Equation (1) we obtain for the mechanical system 110

which becomes, by making substitutions similar to those made above:

$$jp L_2 i_2 + \frac{i_2}{jp C_2} - a_1 L_0 \frac{x}{2} i_0^2 - a_2 \frac{1}{2} L_0 i_1^2 - a L_0 y i_0 i_1 + \frac{D}{C_2} = 0 \quad 115$$

Now it is evident that the term $a_1 L_0 \frac{x}{2} i_0^2$ which is due to the constant pull of the magnet will cancel the term $\frac{D}{C_2}$ which is the constant pull of the spring since the system is in equilibrium. We may also drop $\frac{1}{2} a_2 L_0 i_1^2$, 125

since it is of the second order. Thus

$$i_2 \left(jpL_2 + \frac{1}{jpC_2} \right) - aL_0 y i_0 i_1 = 0 \quad (6)$$

5 We now have the simultaneous equations involving i_1 and i_2 given below:

$$\left. \begin{aligned} aL_0 y i_0 i_2 + i_1 \left(jpL_0 + \frac{1}{jpC_1} \right) &= E \\ i_2 \left(jpL_2 + \frac{1}{jpC_2} \right) - aL_0 y i_0 i_1 &= 0 \end{aligned} \right\} \quad (7)$$

10 Since we are interested in the electrical impedance of this device we solve for E/i_1 from the above equation

$$Z_e = \frac{E}{i_1} = jpL_0 + \frac{1}{jpC_1} + \frac{a^2 y^2 L_0^2 i_0^2}{jpL_2 + \frac{1}{jpC_2}} \quad (8)$$

15 It is evident that the denominator of the last term is the impedance of the mechanical part and we thus see that the electrical impedance of this device is the sum of the reactance of the magnet coil, the series condenser and a term involving the reciprocal of the mechanical impedance. It is thus evident that where the mechanical system is resonant the electrical system will be anti-resonant and vice versa. This is to be expected from the operation of the device since when the mechanical system is vibrating violently or in resonance it will cause the maximum back E. M. F. in the electrical system, thus causing an anti-resonant electrical condition and vice versa.

20 If now we have any complicated mechanical reactance it can be replaced at any one frequency by an equivalent single mass and elastance. Thus at this one frequency, the electrical reactance of the system will be of the same form as (8) with the last term proportional to the reciprocal of the mechanical impedance. Since this process holds good for any frequency whatsoever, we may generalize and say that no matter what non-dissipative mechanical system is used, the electrical reactance will be

$$Z_e = jpL_0 + \frac{1}{jpC_1} + a^2 y^2 i_0^2 L_0^2 \left(\frac{1}{Z_m} \right) \quad (9)$$

25 The above considerations apply specifically to the device of Fig. 1 and it is seen that any characteristic given to Z_m will be reflected in the electrical characteristic Z_e of the device as a whole and that if the source E is replaced by a connection to a transmission line the apparent characteristics of that line will be correspondingly modified either as to impedance at various frequencies, delay in transmission or other properties.

30 Fig. 2 shows a modified form of mechanical device which is essentially a doubling of that of Fig. 1. It consists of two rods of magnetic material to which are attached a number of mechanically tuned reeds, the

whole being actuated by the coils shown. Each rod itself has mass M_5 and is attached to the outside support through springs whose elastance is denoted by S_0 . The two rod arrangement obviates the effects of any mechanical jars on the electrical system since, for similar motion of the rods in the same direction, the reluctance of the magnetic path does not change and, therefore, building vibrations have no electrical effect. The plurality of tuned reeds gives the structure a plurality of resonant frequencies alternating with anti-resonant frequencies.

35 This system may be treated in the same manner as that of Fig. 1 and for it we shall show that

$$Z_e = jpL_{AB} + \frac{2a^2 y^2 i_0^2 L_{AB}^2}{Z_m} \quad (10)$$

40 where Z_m is the mechanical impedance of either of the two equal mechanical systems and L_{AB} is the inductance of the winding AB with the moving part clamped fast in its mean position.

45 Let us suppose that in this double system, each half has the same mechanical constants as the single system shown in Fig. 1. If, for the moment the circuit AB is open and if each mechanical system in the double device receives a displacement q_2 , the total mechanical potential energy will be twice that of the single system.

50 Thus:

$$V = 2 \left(\frac{1}{2} \frac{q_2^2}{C_2} + \frac{Dq_2}{C_2} + \frac{D^2}{2C_2^2} \right) = \frac{q_2^2}{C_2} + \frac{2Dq_2}{C_2} + \frac{D^2}{C_2} \quad 100$$

55 We need not consider the last two terms as they drop out of the final result.

60 The total mechanical kinetic energy of the part which varies and so needs to be considered will also be twice that of the single system since the mass is double.

65 Thus:

$$2 \left(\frac{1}{2} L_2 i_2^2 \right) = L_2 i_2^2 \quad 110$$

70 If, however, we use a system of notation similar to that on the preceding section, that is, where q_2 equals the total change in the length of the air gap, then the displacement of each mechanical system will be $1/2 q_2$. This means that the terms involving mechanical potential and kinetic energies will be effectively halved because the displacement enters as a squared term.

75 Thus:

$$\frac{\left(\frac{1}{2} q_2 \right)^2}{C_2} = \frac{1}{4} \frac{q_2^2}{C_2} \quad 125$$

80 and

$$L_2 \left(\frac{1}{2} i_2 \right)^2 = \frac{1}{4} L_2 i_2^2$$

85 Since these terms finally become the terms

representing mechanical reactance, it is evident that the mechanical impedance will be halved in the result. By a series of steps identical to those for the simple form, we 5 shall have for the electrical impedance of the double system.

$$Z_e = jpL_{AB} + \frac{2a^2y^2i_0^2L_{AB}^2}{Z_m} \quad (10)$$

10 Where Z_m is the mechanical impedance of either half of the device.

Again it is evident that by connecting the points AB to a transmission line or other electric circuit the characteristics of the device will, by reaction, be reflected on the transmission line or circuit. The question of so designing the mechanical device, as to size of masses, strength of springs and so forth, in order to give the desired characteristic to 20 that circuit is of importance and the method which will now be set forth constitutes an essential part of our invention.

Let us suppose, as an illustration, that it is desired to design an electro-mechanical device 25 which shall be the equivalent of the impedances Z_1 or Z_2 described in our copending application, Serial No. 134,928 filed September

$$Z = \frac{-jH(p_1^2 - p^2)(p_3^2 - p^2) \dots (p_{2n+1}^2 - p^2) \dots (p_{2n-1}^2 - p^2)}{p(p_2^2 - p^2)(p_4^2 - p^2) \dots (p_{2x}^2 - p^2) \dots (p_{2n-2}^2 - p^2)} \quad (12)$$

30 11, 1926. That application relates to a network which shall give a desired frequency-delay characteristic to a transmission line.

35 In that application, it is shown that a tandem series of n sections of lattice-type network of constant characteristic impedance K and zero attenuation, as shown in Fig. 3 of this application, can be replaced by a network of the form shown in Fig. 4, in which the impedances Z_1 and Z_2 may have the form of Fig. 5 or Fig. 6 and are related to each 40 other in the manner given by

$$\left. \begin{aligned} Z_1 &= j2K \tan \frac{\beta}{2} \\ Z_2 &= \frac{2K}{j \tan \beta/2} = -j2K \cot \frac{\beta}{2} \end{aligned} \right\} \quad (11)$$

45 In this case, the impedance Z_1 will have a number of resonant frequencies alternating with anti-resonant frequencies and Z_2 will be resonant when Z_1 is anti-resonant and anti-resonant when Z_1 is resonant.

50 In that copending application, a method 55 for designing Z_1 and Z_2 is given to yield the desired delay characteristic. We will now disclose the method we prefer for the design of the electro-mechanical device to give the equivalent of an impedance Z_1 or Z_2 . Solving 60 Equation (10) for Z_m we get

$$Z_m = \frac{2a^2y^2i_0^2L_{AB}^2}{Z_e - jpL_{AB}}$$

65 Where Z_e equals Z_1 or Z_2 , the impedance to be simulated.

The above equation gives the mechanical reactance required. Suppose we desire that the electrical reactance be anti-resonant at the frequencies $p_1 p_3 \dots p_{2n-1}$ then the mechanical reactance will be resonant at these 70 frequencies. The frequencies at which the mechanical reactance will be anti-resonant can be determined from the resonant points of $Z_e - jpL_{AB}$. Having thus found the resonant and anti-resonant frequencies of the 75 mechanical reactance, it is now necessary to find the impedance of this reactance at these frequencies. To do this we make use of a broad theorem given and proven by Foster in an article published in The Bell System 80 Technical Journal, April, 1924, page 259. This "reactance theorem" states that "the most general driving-point impedance Z of a finite resistanceless network whose resonant frequencies (i. e., $Z=0$) are

$$f_1 = p_1/2\pi, f_3 = p_3/2\pi, f_5 = p_5/2\pi, \text{etc.},$$

and whose anti-resonant frequencies (i. e., $Z=\infty$) are

$$f_0 = p_0/2\pi, f_2 = p_2/2\pi, f_4 = p_4/2\pi, \text{etc.},$$

is given by the equation

$$H = \frac{p_0^2 - p_1^2}{p_1^2 - p_0^2} \frac{p_2^2 - p_3^2}{p_3^2 - p_2^2} \dots \frac{p_{2n-2}^2 - p_{2n-1}^2}{p_{2n-1}^2 - p_{2n-2}^2} \dots \frac{p_{2n}^2 - p_{2n-1}^2}{p_{2n-1}^2 - p_{2n}^2} \quad (12)$$

Here H is a constant factor ≥ 0 and $0 = p_0 \leq p_1 \leq p_2 \leq \dots \leq p_{2n-1} \leq p_{2n} = \infty$. H may be calculated from the known value of Z at some particular frequency.

In order to cover all possible cases, p_1 may sometimes equal p_0 and p_{2n-1} may become infinite while H is maintained finite. For example, if the impedance to be constructed is resonant at zero and infinity, then we will let $p_0 = p_1 = 0$ and $p_{2n-1} = p_{2n} = \infty$. This is illustrated by the calculation of Z_1 following. We do not actually use either p_0 or p_{2n} in this case but p_{2n-1} must represent the highest resonant frequency and there must be a frequency $p_{2n} > p_{2n-1}$. We can think of them as $p_{2n-1} = \infty$ and $p_{2n} = \infty + 1 = \infty$ for the sake of convenience. Similarly, if the desired impedance were resonant at zero and anti-resonant at infinity we would have $p_0 = p_1 = 0$ and $p_{2n} = \infty$ but p_{2n-1} would be the highest resonant frequency and not infinity. Keeping the above in mind, together with the fact that resonant frequencies have odd subscripts and anti-resonant frequencies have even subscripts, it is possible to assign the proper values for p_0, p_1 , etc., for any impedance curve.

In order better to see the application of this equation let us consider one of the reeds of Fig. 2 as shown in Fig. 7. Since mass and the reciprocal of elastance are analogous to inductance and capacity, we are justified in saying that the reed must be either an anti-resonant or a resonant device. If we

consider this rod to be actuated by an alternating force of frequency slightly greater than zero, it is evident that the effect of the reed will be entirely due to the mass because the spring will remain stiff. The mass will, by its inertia, give a small positive reactance to the system. As the frequency increases, this positive reactance increases. However, if we consider a very high frequency it will be seen that the mass will tend to stand still with the spring taking up the motion of the rod. Thus, at high frequencies the reactance is negative (due to elastance) and will become less as the frequency increases. But this is what happens in an anti-resonant electrical circuit as shown by the reactance curve of such a circuit in Fig. 8. The reed cannot be resonant because if it were, it would have to have infinite negative reactance at zero frequency and infinite positive reactance at infinite frequency. It must, therefore, be analogous to an anti-resonant circuit. In Fig. 2 there are four such anti-resonant mechanical devices in series. Also the mass M_5 and spring S_0 are in series with the anti-resonant devices. Taking account of the inductance L_{AB} the structure may be represented electrically by the arrangement of coils and condensers shown in Fig. 10. It is thus evident that Foster's theorem applies to the mechanical impedance and can be used in the same way as if we were considering a series of anti-resonant electrical circuits. For the actual constants of this mechanical system we make use of the relation derived by Foster from Equation (12)

$$C_k = \frac{1}{L_k p_k^2} = \frac{jp}{Z_m(p_k^2 - p^2)} \text{ where } p = p_k \quad (13)$$

40

and

$$k = 0, 2, 4, \dots, 2n-2, 2n$$

where C_k is the reciprocal of the elastance and L_k is the mass for the k th tuned reed. It should be noted that the subscript k is not the same as on Fig. 2, since k is always even for anti-resonant devices (see Fig. 6).

The equation shown above gives the values for the tuned reeds in terms of the constant H (see Equation (12)). This constant may be determined from a knowledge of the reactance desired at some particular frequency.

In all, there are four different conditions which may have to be met by the mechanical device. They are: (a) The electrical impedance of the device may be required to be zero at zero frequency and zero at infinite frequency, or (b) zero at zero frequency and infinite at infinite frequency, or (c) infinite at both zero and infinite frequencies, or (d) infinite at zero frequency and zero at infinite frequency. It will be evident that the device as shown in Fig. 2 has zero impedance at

zero frequency, but infinite impedance at infinite frequency.

Supposing we wish the device to have zero impedance at zero frequency, and zero impedance at infinite frequency, this being the condition expressed in connection with Z_1 in our copending application referred to. This can be accomplished by putting a condenser C_{AB} across the terminals A and B. We can now write the equation for the electrical impedance of the device, with the condenser in parallel to the remainder of the electrical circuit, as

$$Z_e = \frac{1}{jpC_{AB}} \left(\frac{jpL_{AB} + \frac{2a^2L_{AB}^2y^2i_0^2}{Z_m}}{1 + jpL_{AB} + \frac{2a^2y^2i_0^2L_{AB}^2}{Z_m}} \right) \quad (10a)$$

We may solve this equation for Z_m since all the other values in the equation are known. Then the masses and springs of Z_m may be computed by Foster's theorem as explained above. If we wish the device to have infinite reactance at zero frequency this can be accomplished by putting a condenser in series. It is evident that Z_m can be calculated for any combination such as this where condensers are used either in series or in parallel. We must, of course, know what impedance is desired at zero and infinite frequencies before we can put in the condensers and solve for Z_m .

The application of this method of design and the results arising from the invention will be more clearly illustrated by a concrete problem. Let this problem consist of the design of the electro-mechanical device of Fig. 2 to be the equivalent of the impedance Z_1 of Fig. 4, which is to have zero impedance at zero frequency and at infinite frequency. Here the Equation (13) applies and we may solve for Z_m giving

$$Z_m = \frac{2L_{AB}a^2y^2i_0^210^7 \left[\frac{1}{jpC_{AB}} - Z_1 \right]}{Z_1 \left[\frac{1}{jpC_{AB}L_{AB}} + jp \right] - \frac{1}{C_{AB}}} \quad (14)$$

It will be noted that a factor 10^7 has been introduced to reduce the electrical measurements, which are ordinarily made with the practical units, to absolute units (1 Joule = 10^7 ergs). With this adjustment, the results for masses will be in grams and for elastance in dynes per centimeter.

It is necessary to choose suitable values for L_{AB} , C_{AB} , a , y , i_0 , and knowing Z_1 , from the characteristics of the circuit to be replaced, the impedance Z_m may be computed.

In order to design the elements of Z_m it is only necessary to know the frequencies at which Z_m becomes zero and infinite and the value of Z_m at some intermediate frequency, in order to determine the constant H of Equation (12).

In order to obtain satisfactory results, reasonable assumptions must be made. Let us take

$$\begin{aligned} L_{AB} &= .2 \text{ henry} \\ i_0 &= .1 \text{ amperes} \\ C_{AB} &= .013 \text{ M. F.} \\ a &= .905 \\ y &= 85 \\ k &= 600 \text{ ohms} \end{aligned}$$

Since Z_m is proportional to $a^2 y^2 i_0^2$, we may vary the size of Z_m at will without changing the electrical impedance, merely by adjusting one or more of the factors a^2, y^2, i_0^2 . Also, if it is desired to vary one of these factors without changing Z_m one or more of the other factors may be adjusted so that the product remains constant.

Z_1 , which we are to replace, is one of two impedances with the hybrid coil arrangement of Fig. 4 which was designed to replace a tandem series of six sections of lattice network of the type shown in Fig. 3 and as described in our copending application referred to above. These six sections had a delay characteristic shown by curve *b* of Fig. 9. In order to simulate this delay, it developed that Z_1 should have a value given by

$Z_1/j2K = \tan \frac{\beta}{2}$ and this relation is plotted as curve *c* of Fig. 9. It will be observed that the frequencies at which Z_1 should be reso-

nant and anti-resonant are clearly shown and thus curve *c* must be used in our present problem.

In order to determine the frequencies corresponding to $p_1, p_3, p_5, \dots, p_{2n-1}$ at which the mechanical part is resonant, that is at which Z_m is zero, equate the numerator of (14) to zero, whence, for these frequencies:

$$Z_1 = \frac{1}{jpC_{AB}}$$

Since $Z_1 = j2K \tan \frac{\beta}{2}$ (15)

$$\tan \beta/2 = -\frac{1}{p^2 K C_{AB}}$$

Inserting the values of K and C_{AB} , (15) is plotted on Fig. 9 as curve *d*. Its intersections with curve *c* give the frequencies at which such resonance occurs, as

$$\begin{aligned} f_1 &= 540 \\ f_3 &= 836 \\ f_5 &= 1006 \\ f_7 &= 1210 \\ f_9 &= 1471 \\ f_{11} &= 2515 \end{aligned}$$

In order to determine the frequencies corresponding to $p_2, p_4, p_6, \dots, p_{2n-2}$ at which the mechanical part is anti-resonant, that is, at

which Z_m is infinite, equate the denominator of (14) to zero, whence,

$$Z_1 = \frac{jpL_{AB}}{1 - p^2 C_{AB} L_{AB}}$$

$$\therefore \tan \beta/2 = \frac{pL_{AB}}{2K - p^2 K C_{AB} L_{AB}} \quad (16)$$

Again (16) is plotted on Fig. 9 as curve *e* and its intersections with curve *c* give the frequencies at which such anti-resonance occurs as

$$\begin{aligned} f_0 &= 0 \\ f_2 &= 780 \\ f_4 &= 956 \\ f_6 &= 1157 \\ f_8 &= 1405 \\ f_{10} &= 2105 \\ f_{12} &= \infty \end{aligned}$$

Using the above data, the two expressions (12) and (14) for Z_m are solved simultaneously at a given frequency. Let us take 600 cycles, at which frequency $\tan \beta/2 = -2.601$ making $Z_1 = -j3122$, which gives $H=5$.

We may now solve for the springs and masses using Equations (12) and (13), which are here restated:

$$C_k = \frac{1}{L_k p_k^2} = \frac{jp}{Z_m(p_k^2 - p^2)} \quad (13)$$

where $p = p_k$ and $k = 0, 2, 4, \dots$

$$Z_m = -jH \frac{(p_1^2 - p^2)(p_3^2 - p^2) \dots (p_{2n-1}^2 - p^2)}{p(p_2^2 - p^2)(p_4^2 - p^2) \dots (p_k^2 - p^2) \dots (p_{2n-a}^2 - p^2)} \quad (12)$$

The expression (13) contains a term

$$\frac{(p = p_k)}{(p_k^2 - p^2)}$$

which will cancel the same term in (12), when (13) is substituted in (12) and thus keeps the expression determinate. The value of C_k is then obtained directly and L_k is obtained from C_k . The values obtained for the particular problem under discussion are as follows:

Springs, centimeters per dyne	Masses, in grams
$C_0 = 0.0798 \times 10^{-7}$	
$C_2 = 0.407 \times 10^{-7}$	$L_2 = 1.022$
$C_4 = 0.456 \times 10^{-7}$	$L_4 = 0.607$
$C_6 = 0.367 \times 10^{-7}$	$L_6 = 0.516$
$C_8 = 0.260 \times 10^{-7}$	$L_8 = 0.494$
$C_{10} = 0.0341 \times 10^{-7}$	$L_{10} = 1.677$
	$L_{12} = 5.00$

In terms of the symbols used in Fig. 2, $C_0 = S_0$; $L_{12} = M_5$; and C_{12} and L_0 are not present.

The springs $S_1, S_2, S_3, \dots$ are just twice the value of $C_2, C_4, C_6, \dots$ while the masses $M_1, M_2, M_3, \dots$ are just $1/2$ the value of $L_2, L_4, L_6, \dots$ since they occur in pairs.

In obtaining these results, certain boundary conditions are helpful. Since the device

is to have zero impedance at zero and at infinite frequency, it is evident that $C_{12}=0$ and $L_0=\infty$, i. e., these two elements are not present. From Equation (12), taken at $p=\infty$, it appears that $L_{12}=H=5$ grams. Also from Equation (12), taken at $p=0$, it appears that

$$C_0 = \frac{p_2^2 p_4^2 \dots p_{2n-2}^2}{H p_1^2 p_3^2 \dots p_{2n-1}^2}$$

- 10 From the value of C_0 , it is seen that the spring S_0 is a very stiff one for a force of 10^6 dynes (about 2 pounds) will stretch it only $10^6 \times 0.0798 \times 10^{-7} = 0.00798$ cm. If this is too stiff to make easily the mechanical impedance may then be lowered. That is, multiply all C 's by a desired factor and divide all L 's by the same factor. If the electrical impedance is to remain unchanged, it is necessary to also lower $a^2 y^2 i_0^2$ by the same factor as explained above.

For example, let the impedance of the mechanical system be reduced to $1/10$. Then we change the decimal points in the results as given above, so that all springs are ten times as movable and masses are $1/10$ previous values. In order to keep the electrical impedance the same, we must reduce $a^2 y^2 i_0^2$ to $1/10$ which may be accomplished, for example, by taking

$$y = \frac{85}{\sqrt{10}} = 26.9$$

- 35 The particular characteristics of the circuit of Fig. 4 are such that, as mentioned, Z_1 and Z_2 are related in the manner given by Equation (11). This implies that Z_2 is resonant and anti-resonant when Z_1 is anti-resonant and resonant. By a procedure similar 40 to the preceding, Z_2 could now be designed bearing in mind that a curve corresponding to

$$\frac{2K}{jZ_2} = \tan \frac{\beta}{2}$$

- 45 which is the reciprocal of curve c of Fig. 9, would be used. Because of the boundary conditions C_{AB} would be connected in series and not in parallel. As a result, the complex structures Z_1 and Z_2 , which have been originally planned as wholly electrical, can be replaced by devices which are mainly mechanical, with the attendant advantages.

- 55 While, in this specification, a special application of the invention has been illustrated in connection with the delay circuit of Fig. 4, it is to be understood that it is for illustrative purposes only and is not limited to such applications. For this reason, it is to be understood also that various modifications can be made in the structure of Fig. 2, whether it is to be used in this type of delay circuit or for other purposes, without departing 60 from the spirit of our invention.

What is claimed is:

1. In a wave delay structure an electro-mechanical device comprising tuned mechanical parts associated with an electric circuit, the mechanical parts being so designed as to dimensions that the device reacts by reflection on the electric circuit in accordance with and to give a desired delay-frequency characteristic. 70

2. An electro-mechanical device comprising a plurality of tuned mechanical parts, a winding associated with said mechanical parts and means for connecting said winding to an electric circuit, the mechanical parts being so designed as to dimensions that the device reacts by reflection on the electric circuit to give a desired non-dissipative impedance and delay characteristic thereto. 75

3. An electro-mechanical device comprising a plurality of tuned mechanical parts, a winding associated with said mechanical parts and means for connecting said device to an electric circuit, the tuned mechanical parts being so designed as to frequency that the device reacts by reflection on the electric circuit in accordance with and to give a desired delay-frequency characteristic. 80

4. An electro-mechanical device adapted to serve as a substitute for an electrical delay network, said device comprising a plurality of tuned mechanical parts so designed as to dimensions that the said parts react by reflection to give a delay characteristic equivalent to that of the network to be replaced. 85

5. An electro-mechanical device designed to simulate a non-dissipative electrical delay network of given characteristics with resonant and anti-resonant frequencies, said device comprising vibratory mechanical members tuned to frequencies determined by the resonant and anti-resonant frequencies of the network to be simulated. 90

6. An electro-mechanical device designed to simulate a non-dissipative electrical delay network of given characteristics, said device comprising vibratory mechanical members and a winding associated with said members, the dimensions of the winding and the frequency of the members being so designed as to give by reflection a non-dissipative delay characteristic to the device equivalent to that of the network to be simulated. 95

7. An electro-mechanical device designed to simulate an electrical network of given characteristics and consisting of a plurality of parallel branches of series inductance and capacity with resonant and anti-resonant frequencies, said device comprising a winding with a movable magnetic core, a support, a spring attaching the core to the support, and a plurality of similar vibratory elements attached to the core, the core and spring and the vibratory elements being tuned to frequencies determined by the resonant and 100

anti-resonant frequencies of the network to be simulated.

8. An electro-mechanical device designed to simulate an electrical network of given delay characteristics with resonant and anti-resonant frequencies, said device comprising a winding and a plurality of tuned mechanical parts, each of said tuned mechanical parts comprising a spring member 10 and a mass, each of said parts being tuned to a frequency determined by the resonant and anti-resonant frequencies of the network to be simulated.

9. In a transmission line, a delay correction network comprising a hybrid coil and two non-dissipative impedances associated therewith, the said impedances being mainly mechanical, the parts being so designed as to react on the electrical circuit to give the desired delay characteristic.

10. In a delay transducer of a predetermined delay-frequency characteristic, a composite electrical and mechanical device comprising electrical elements and mechanical 25 elements, means for impressing a complex electrical wave on the electrical part, the mechanical part being designed to convert the electrical wave into a mechanical wave, to transmit this wave and reflect it back into the electrical part with a delay for each component of the wave to yield an overall delay equal to the predetermined delay-frequency characteristic.

11. A phase delay compensator adapted to 35 be associated with a transmission line comprising a transformer and a complex impedance, said impedance comprising electrical elements and mechanical elements and having resonant and anti-resonant frequencies, 40 the constants of the impedance having values which bear a definite relation to the delay of an equivalent lattice network at each resonant and anti-resonant frequency.

12. In a delay transducer of a predetermined delay-frequency characteristic, a composite electrical and mechanical device comprising electrical elements and mechanical elements, means for impressing a complex wave on the electrical part, the mechanical 50 part being so designed that the impedance of the composite device is equal to the electrical impedance plus a multiple of the reciprocal of the mechanical impedance.

13. An electro-mechanical device designed 55 to simulate an electrical network of given characteristics and having resonant and anti-resonant frequencies, said device comprising a winding with a movable magnetic core, a support, a spring attaching the core to the 60 support, and a plurality of similar vibratory elements attached to the core, the core and spring and the vibratory elements being anti-resonant and resonant at approximately the frequencies for which the network to be simulated is resonant and anti-resonant.

In testimony whereof, we have signed our names to this specification this 10th day of September 1926.

HARRY NYQUIST.

KENNETH W. PFLEGER.
